PAUL SCHUYLER VAN BLOEM, OF HEMPSTEAD, NEW YORK, ASSIGNOR TO VIKING PRODUCTS CORPORATION, OF NEW YORK, N. Y., A CORPORATION OF PENNSYLVANIA.

SIGN.

Application filed September 5, 1925. Serial No. 54,772.

This invention relates to signs and one of its objects is to provide a sign comprising a translucent plate adapted to be illuminated from the rear and formed with impressed 5 indicating characters in its rear face, the material and form of the plate being such that the said characters will be invisible from the front when the plate is unilluminated but will become distinctly visible 10 upon the illumination of the plate.

A further object is the provision of a translucent sign plate bearing indicating characters at its rear face and adapted when unilluminated to present a uniform color 15 tone with the said characters invisible from the front. When the plate is illuminated from the rear the characters and the area surrounding them will both appear in the same color but in contrasting tones, and the 20 characters will be rendered clearly distinguishable.

In the drawings, Fig. 1 is a front elevation of the sign plate mounted on a lamp casing;

25 Fig. 2 a section on the line 2—2 of Fig. 1;

Fig. 3 a fragmentary rear face view of the sign plate;

Fig. 4 an enlarged section through the sign plate taken on the line 4—4 of Fig. 3; 30 and

Fig. 5 a view similar to Fig. 1, upon a reduced scale, showing the effect produced when the sign plate is illuminated.

Referring to the parts by numerals, 1 35 designates the sign or signal plate which is formed of translucent or colored glass. The plate 1 is adapted to be illuminated from the rear and at its rear or light-receiving face 2, characters 3, in reverse, are deeply 40 impressed or molded in the plate. As shown in the drawing the characters are the letters of the word "Down". The characters are defined by depressions 4 of material depth which are formed in the plate when it is 45 molded. Each depression has straight side walls 5 and a flat bottom 6. The plate is made larger than the over-all dimensions of the characters in order to provide a surrounding field, and the thickness of the 50 plate throughout said surrounding field is substantially uniform. The rear or light-receiving face 2 of the plate is preferably flat and smooth, while the front or light-

transmitting face is slightly roughened as at 7 to adapt it to diffuse light.

As shown in the drawings the plate is mounted over the open front of a casing C and a lamp L is suitably located and mounted within the casing to properly illuminate the plate. The casing is adapted to exclude 60 outside light from the rear face of the plate. It will be understood, of course, that the lamp and sign could be mounted in other ways than the one shown.

The plate 1 is of uniform color and 65 formed of glass that is uniform in character throughout its thickness, both as to color and as to structure. This glass is adapted to offer a degree of light obstruction proportional to its thickness. The depressions 4 70 are of considerable depth and therefore greatly reduce the thickness of the plate between the bottoms of the depressions and the front face of the plate, but said thickness is sufficient to render the depressions invisible 75 from the front of the plate when the rear is unilluminated.

When the lamp L is illuminated many of the light rays which fall upon the field surrounding the characters will be obstructed or absorbed when they enter the thick portion of the plate, while the portion of the plate which is reduced in thickness by the character depressions will offer far less obstruction to the light rays which fall in the 80 depressions. As a result the front face of the plate will present the appearance of a brightly luminous sign or signal portion and a materially less luminous surrounding field. This contrast in luminosity will render the 85 indicating characters clearly distinguishable as indicated in Fig. 5. The translucent glass forming the plate may be either colored or uncolored. If colored glass is used both the characters and the surrounding field will 90 appear in the same color when illuminated, but the tone of the field will be much darker than that of the characters.

When the lamp L is unilluminated the characters will be invisible and the appearance of the front face of the signal plate will be uniform over its entire area both as to color and tone, as indicated in Fig. 1. This is because of the exclusion of light 100 from the rear face of the plate by the casing, 105 and because the roughened front face 7 of

the plate causes a diffuse reflection of the light which falls upon it from the outside. This diffuse reflection at the front face of the plate masks the characters formed at the 5 rear face.

In the drawing the plate is shown as formed with characters suitable to an elevator signal. It will be understood, however, that such a plate is easily adaptable for 10 sign purposes also by merely varying the form of the indicating characters. The tone and luminosity of the plate may be varied to suit the different requirements, by varying the opacity of the glass and the thickness of 15 the plate. In the case of an elevator signal it is desirable that considerable illumination appear through both the characters and the surrounding field in order to quickly attract attention to the approach of a car and 20 the direction of its travel.

What I claim is:

1. A sign body of translucent glass formed with a light-diffusing front face and formed in its rear face with a relatively deep 25 depression conforming in outline to an indicating character, the glass of said body providing a degree of light obstruction proportional to its thickness and the body being larger than the over-all dimensions of 30 the said depression outline with the portion of the body surrounding the depression of greater thickness between said front and rear faces than the thickness of the portion between the bottom of the depression and 35 said front face, this latter portion being of sufficient thickness to conceal the depression when not illuminated, whereby when the body is illuminated from the rear the character will be rendered distinguishable

through the front face and will appear more 40 luminous than the portion of the body surrounding it, and whereby when the body is unilluminated at the rear the character will be indistinguishable from the front.

2. A sign plate of translucent glass 45 formed with a roughened light-diffusing front face, and with a rear face including an area conforming in outline to an indicating character and an area surrounding said character area, the glass of the plate providing a degree of light obstruction proportional to its thickness and the portion of the plate between the front face and the character area of the rear face being of different thickness than the portion between 50 the front face and the character-surrounding area of the rear face, whereby when the plate is illuminated at the rear the character and the surrounding portion will appear with contrasted luminosity when viewed 55 from the front, and whereby the character will be invisible when the plate is unilluminated.

3. A sign device comprising a casing, a lamp therein, a translucent glass plate 60 mounted in said casing to exclude outside light from the rear face of said plate and to expose the front face, the rear or inner face of said plate being formed with relatively deep character depressions, said depressions 65 being invisible from the front when the rear face of the plate is unilluminated, and the front face of the plate being roughened to cause a diffuse reflection of the light rays 70 falling thereon from outside the casing. 75

In testimony whereof I hereunto affix my signature.

PAUL SCHUYLER VAN BLOEM.
